United Shoe Machinery Corporation, Paterson,
N. J., a corporation of New Jersey

Application April 26, 1934, Serial No. 722,539

20 Claims. (Cl. 12—4)

This invention relates to machines for use in the manufacture of shoes for shaping uppers over lasts and is herein illustrated as embodied in a machine of the same general type as disclosed in Letters Patent No. 1,583,044, granted on May 4, 1926, upon an application filed in the name of C. H. Hoyt, for lasting the heel ends of shoes. It is to be understood, however, that in its more general aspects the invention is not limited to machines of that type nor to heel-end lasting machines.

In machines of the above-mentioned type the margin of the heel end of the upper is wiped inwardly over a shoe bottom part such as a sole or insole, mounted on a last, by wipers which are mounted for bodily advancing movement lengthwise of the shoe and swinging or closing movements laterally of the shoe to wipe the upper inwardly substantially the same distance from the edge of the shoe bottom both at the end and at the sides of the heel seat. In such machines there is provided means for adjusting the wipers toward or from each other to vary their initial open positions to accommodate shoes of different sizes, such an adjustment correspondingly varying the limits of the closing movements of the wipers as required by the different sizes. Variation in the limits of the closing movements is also sometimes required for the best results by differences in style, especially differences involving wide variations in the widths of the shank portions of the shoes. It has been found, however, that if the wipers are positioned initially near enough together to produce the best results at the end of the wipe at the forward portion of the heel seat in operating, for example, on shoes having very narrow shank portions, they may not be in the best positions to begin the overwiping operation at other portions of the heel seat.

In view of the above, an object of the present invention is to provide improved wiper-operating means so constructed that the limits of the closing movements of the wipers may be varied without altering substantially their positions relatively to each other at the beginning of their closing movements. In the illustrated construction, as in that disclosed in the above-mentioned Letters Patent, the wipers are advanced by an operating member which is mounted for rectilinear movements in directions lengthwise of the shoe, and connected to this member are slides movable laterally of the shoe at its opposite sides for imparting to the wipers their closing movements in predetermined time relation to their advancing movement. The wipers are connected to the clos-

ing slides by plates having guide slots therein extending in directions lengthwise of the shoe and in which are movable rolls carried by the wipers, the plates thus acting to guide the wipers in their operative movements. For varying the limits of the closing movements of the wipers the plates, in the construction shown, are adjustable relatively to the closing slides to positions in which their guide slots are in angular relation to the direction of the movement of the wipers lengthwise of the shoe, so that more or less closing movement is imparted to the wipers in response to their movement lengthwise of the shoe in addition to that derived from the movements of the closing slides. Provision is accordingly afforded for varying the amount and therefore the limits of the closing movements of the wipers, the construction being such that the initial positions of the wipers are substantially unaffected by the adjustment of the plates on the closing slides. Preferably, and as shown, separate means is provided for adjusting each guide plate relatively to its closing slide to permit the amount of closing movement imparted to each wiper to be varied independently of the amount of closing movement imparted to the other wiper. This permits an adjustment such that the wiper operating at the inner side of a right or a left shoe will receive a greater closing movement than the wiper at the outer side, as may be required for the best results in operating on some styles of shoes.

In machines of the type illustrated the upper, in the heel-end lasting operation, is clamped around the heel end of the last by a heel band which for best results should apply substantially uniform pressure to the upper at the opposite sides of the shoe and should position the shoe with the median line of its heel-end portion substantially in alinement with the path of the meeting point of the wiper edges as the wipers advance lengthwise of the shoe. To permit the proper positioning of each shoe by the band and the positioning of the shoe also in proper relation to the plane of the wipers, the invention provides, as a further feature, improved shoe-supporting means arranged to permit bodily movement of the shoe laterally to centralize the heel end of the shoe relatively to the wipers while permitting the shoe also to be tipped relatively to the wipers to position the heel seat in proper relation to the plane of the wipers without any substantial lateral displacement of the heel end of the shoe relatively to the band. The shoe is thus supported in proper relation to the heel band and to the

wipers notwithstanding such variations as there may be in the angular relation of different spindle holes to the bottom faces of different lasts or variations in the locations of different spindle holes laterally of the heel ends of different lasts.

The above and other features of the invention, including various novel details of construction and combinations of parts, will now be more particularly described by reference to the accompanying drawings and pointed out in the claims.

In the drawings,

Fig. 1 is a view, partly in plan and partly in section of a portion of a heel-end lasting machine in which the present invention is embodied;

Fig. 2 is a side elevation, partly in section, of the shoe-supporting means;

Fig. 3 is a view, partly in front elevation and partly in section, of the shoe-supporting means shown in Fig. 2 and illustrating the relation of the parts to the lasting instrumentalities of the machine when operating on a shoe mounted on a last in which the spindle hole is not located at uniform distances from the opposite side faces of the heel-end portion of the last; and

Fig. 4 is a section on the line IV—IV of Fig. 1.

The invention, as previously stated, is herein illustrated as embodied in a machine of the same general type as that disclosed in the above-mentioned Letters Patent, portions of the machine shown being constructed as further disclosed in Letters Patent No. 1,852,015, granted April 5, 1932, on an application filed in my name. Accordingly, only such portions of the machine as it is necessary to refer to for an understanding of the invention will be described herein in detail. Machines of this type are designed especially for the shaping of shoe upper materials *a* (herein referred to inclusively as the upper) about the heel end of a last *b* and include means for wiping the margin of the upper inwardly over a sole or insole *c* on the last and means for driving a plurality of fastenings such as tacks to fasten the margin of the upper in overwiped position. Such machines comprise a shoe support or jack, hereinafter more particularly referred to, upon which the shoe is supported and by swinging movement of which the shoe is positioned with its heel end within a heel-embracing band *d*. This heel band is supported in the machine and is closed about the heel end of the shoe in the power operation of the machine by mechanism fully shown and described in the above-mentioned Letters Patent No. 1,583,044, and which need not be described herein. In the course of the operation of the machine the shoe is engaged on the heel seat by a hold-down member or presser foot *e* also automatically controlled as disclosed in the above mentioned Letters Patent No. 1,583,044, and cooperating with the jack to determine the heightwise position of the shoe relatively to the wiping and fastening mechanism of the machine.

For wiping the margin of the upper inwardly over the sole about the heel end of the last the machine is provided with a pair of wipers *f* and *g* mounted for swinging movements about an axis located at the meeting point of the wiping edges of the wipers. The wipers *f* and *g* are maintained in proper relation to each other and are guided for swinging movements about their common axis by means which is substantially the same as that fully shown and described in the prior Letters Patent No. 1,852,015. As more fully shown in said Letters Patent, the wipers are mounted on a wiper holder comprising a slide *h* which is mounted in a guideway in the head of

the machine for rectilinear movements lengthwise of the shoe to advance and retract the wipers. The slide *h* is provided at its rear end with a cylindrical projection *i* mounted in a socket in the head to assist in guiding it. The slide *h* is operated to impart to the wipers *f* and *g* their movements lengthwise of the shoe by means which is substantially the same as that shown and described in the above mentioned Letters Patent No. 1,583,044.

For imparting to wipers *f* and *g* swinging or closing movements in automatically determined time relation to their advancing movement lengthwise of the shoe, in general similarity to the organization disclosed in the prior Letters Patent No. 1,852,015, there are mounted in guideways in

the opposite sides of the head of the machine slides *j* (Fig. 1), one for each of the wipers, and each slide has connected thereto by means of a screw *k* a member or plate *l*, hereinafter more particularly referred to, in which there is formed a slot *m* to receive a roll *n* carried by the adjacent wiper. A cover plate *o* (Fig. 4) overlaps the slides *j* and is provided with slots *p* in which upstanding portions of the screws *k* are movable. For imparting operative movements to the slides *j* the wiper-supporting slide *h* carries a member *q* provided on each of its opposite sides with a series of rack teeth *r* in engagement with a curved rack *s* formed on one end of a lever *t* which is pivotally mounted at *u* on the head of the machine. On the opposite end of the lever *t* is a curved rack *v* which engages and operates a pinion *w* in engagement with teeth formed on a rack member *x* secured adjustably by a screw *y* in a recess in the slide *j*. It will thus be seen that as the wiper-supporting slide *h* moves forward to advance the wipers lengthwise of the shoe the slides *j* through the connections described are moved inwardly toward the shoe to impart closing movements to the wipers and as the slide *h* is retracted the slides *j* are likewise retracted to open the wipers. It will be understood that by the elongated slots *m* and the rolls *n* operative connections are maintained between the slides *j* and the wipers in all positions of the wipers lengthwise of the shoe.

Similarly to the disclosure of the prior Letters Patent, the connections between the member *q* and the slide *h* are such that by adjusting this member relatively to the slide the wipers may be adjusted in unison about the axis of their swinging movements to position them in proper relation to each other for operating on shoes of different sizes. For this purpose the member *q* is mounted in a recess in the slide *h* with provision for limited movements lengthwise of the shoe and is provided with a pair of downwardly extending lugs *z* (Fig. 1) which fit within recesses formed in a block *aa* also movable lengthwise of the slide *h* and provided with a bore having screw threads engaged by the threads of a shaft *bb*. The shaft *bb* is rotatably mounted at its opposite ends in bearing blocks *cc* which are inserted in recesses in the slide *h*, and fast on the shaft is a bevel-gear *dd* engaged by another bevel-gear *ee* provided with a cylindrical stud *ff* mounted in a bearing in one side of the slide *h*. It will thus be seen that by turning the gear *dd* the interiorly threaded block *aa* may be moved in one direction or the other lengthwise of the shoe, carrying with it the member *q* upon which the rack teeth *r* are formed, and that through the connections between these rack teeth and the slides *j* the wipers are adjusted about the axis *u*.

of their swinging movements. For turning the gear 64 there is mounted in the head of the machine a shaft 68 having on its inner end a tongue 70 arranged to enter a recess 72 formed in the stud 66 when the shaft 68 is moved inwardly from the position illustrated in Fig. 1. The shaft 68 may thus be moved inwardly against the resistance of a spring 74 which acts normally to hold it disconnected from the stud 66 and thus to avoid interference with the operative movement of the slide 18. When the parts of the machine are in starting positions, as illustrated in Fig. 1, the shaft 68 is in alignment with the stud 66 and the tongue 70 may be connected to the stud by pushing the shaft inwardly. Thus by the use of a hand wheel 76 on the shaft the required adjustment of the wipers laterally of the shoe may be made.

In the illustrated machine the margin of the upper is secured in lasted position on the heel seat by upper-fastening tacks which are driven through openings in the wipers in locations near their wiping edges by means carried by the wipers. This means may be and preferably is the same as the means fully shown and described in the above-mentioned Letters Patent No. 1,852,015 and accordingly need not be described in detail.

In the machine herein shown there is further provided for purposes of this invention means for varying the amount of closing movement imparted to each of the wipers 14 and 16 without substantially altering the adjusted positions of the wipers relatively to each other laterally of the shoe when the machine is initially at rest. It will be understood that as the wipers are advanced by the forward movement of the slide 18 closing movements of predetermined extent are imparted to the wipers by the inward movements of the slides 22 and that the wipers are guided in their movements lengthwise of the shoe by the rolls 30 and the slots 28 formed in the plates 26 on the slides 22. In the illustrated construction the plates 26 are mounted on the slides 22 for movements about axes which are so located as to permit the plates to be adjusted relatively to the slides without imparting to the wipers any swinging movements toward or from each other widthwise of the shoe when the wipers are in their open positions. As shown, particularly in Figs. 1 and 4, each plate 26 has formed on its upper face a curved tongue 78 lying in a curved slot 80 in the slide 22, and on its inner side face each plate is provided with a curved rack 82 which is engaged by a pinion 84 carried by the slide 22. Engaging the teeth of each pinion 84 is a rack member 86 which is slidably mounted in a recess in the slide 22 and to which movements in directions lengthwise of the slide may be imparted by an adjusting screw 88 threaded in the slide and provided with spaced shoulders engaging the opposite side faces of a projection 90 on the rack member, the construction being such that by movement of the screws 88 the plates 26 may be adjusted relatively to the slides 22 without varying the relative positions of the wipers and the slides. The slots 28 are so formed that when the plates 26 are in the adjusted positions shown in Fig. 1 substantially no additional closing movements are imparted to the wipers in the forward movement of the slide 18 by reason of the movement of the rolls 30 along the slots 28. Outward movements of the rack members 86 along the slides 22, however, will impart to the plates 26 swinging movements in directions to carry the forward ends of the slots 28 toward each other and thus to cause addi-

tional closing movements to be imparted to the wipers in response to the movement of the wipers lengthwise of the shoe by reason of the angular relation of the slots 28 to the direction of such movement. Each rack member 86 may be adjusted relatively to its slide 22 within limits determined by a pin 92 which is carried by the slide 22 and is arranged to engage the rack member at the opposite ends of a slot 94 formed in the rack member. Each slide 22 has formed therein an arcuate slot 96 concentric with the curved tongue 78 on the plate 26 and through which extends the reduced shank portion 98 of the screw 24. As shown particularly in Fig. 4, the screw 24 is threaded in the plate 26 and has a shoulder 99 which bears on the upper surface of the slide 22. As the screw is tightened it thus acts to hold the plate 26 in any position of adjustment relatively to the slide 22 into which it may be moved.

It will be evident that by this adjusting means the amounts and accordingly the limits of the closing movements imparted to the wipers may be varied to take care of wide variations in the shapes of the heel-end portions of shoes of different styles and particularly shoes the shank portions of which vary greatly in width. The plates 28, moreover, may be adjusted differently to cause a greater closing movement to be imparted to one of the wipers than that imparted to the other wiper when operating on shoes the opposite sides of the heel-end and shank portions of which differ considerably in curvature. These adjustments, as hereinbefore described, are made without varying substantially the relation of the wipers to each other when they are in their open positions. It will thus be seen that the wipers may be so operated under varying conditions that not only will the margin of the upper be wiped inwardly over the sole for substantially its entire width around the end and along the opposite sides of the heel end of the shoe, but by reason of the locations of the wipers at the end of their closing movements the upper-fastening tacks will be inserted at substantially uniform distances from the edge of the shoe bottom around the entire heel seat. It will be understood that in addition to adjusting the plates 26 in the manner described, when required by the character of the work, the operator also will adjust the wipers preliminarily toward or from each other as heretofore for shoes of different sizes by use of the hand wheel 76.

In order to produce the best results at and near the junction of the heel-end and shank portions of shoes it is desirable, particularly on welt work, to subject the upper to an inward wipe in locations forwardly of the heel seat. For this purpose, as herein shown, the wipers 14 and 16 are each provided with forwardly extending offset portions 99 arranged to wipe the portions of the margin of the upper just forwardly of the heel breast line inwardly over the feather and against the rib of the insole.

The means for supporting the last and shoe for the operations hereinbefore described comprises a jack mounted for swinging movements in directions lengthwise of the shoe to carry the shoe into and out of lasting position in the same general manner as illustrated in Letters Patent No. 1,558,737, granted October 27, 1925, upon an application of R. F. McFeely, the jack comprising a casing 100 in which there is mounted a post 102 (Figs. 2 and 3) which carries a heel pin or spindle 104 adapted to project into the usual spindle-hole provided in the heel end of a last. It will be understood that after mounting the shoe and last on 75

the jack and prior to the starting of the machine the operator, as in the use of prior machines, swings the jack rearwardly to carry the shoe into the heel band 10. In the power operation of the machine the upper is clamped around the heel end of the last by the heel band before the margin of the upper is wiped inwardly over the sole by the wipers. To permit each shoe to be positioned with the heel seat substantially parallel to the plane of the wipers notwithstanding such variations as there may be in the angular relation of the spindle holes to the bottom faces of the different lasts, the illustrated machine is provided with means which is substantially the same as that disclosed in Letters Patent No. 1,896,121, granted February 7, 1933, upon an application of mine. As more fully shown and described in said Letters Patent, there is mounted at the upper end of the post 102 in a laterally extending slot 106 a block 108 which carries the spindle 104. For engaging the top face of the cone of the last there is mounted on the block 108 a plate 109 provided at its opposite edges with downturned flanges 111 having arcuate lower edges supported on similarly curved shoulders of the block, the plate being provided with an opening 113 considerably larger than the spindle 104 and through which the spindle extends. The slot 106 is formed to provide a guideway for the block 108 curved about an axis which extends lengthwise of the shoe and is located as indicated at y (Fig. 3) substantially at the heel seat face of the shoe. By movement of the block 108 in the slot a tipping movement may be imparted to the shoe to position the opposite sides of the heel seat in the same relation to the wipers without substantial bodily lateral displacement of the shoe relatively to the post 102. It will be understood that the block 108 and the spindle 104 are normally centralized by spring means (not shown) and that the block and spindle may be moved against the resistance of said spring means in one direction or the other to impart to the shoe its tipping movement. It will be understood also that such movement may be effected by the operator as he presents the shoe to the machine or the movement may result from excess of pressure of the wipers on one side or the other of the heel seat, the arrangement being such that if the shoe is not presented initially in position to receive substantially the same wiper pressures at the opposite sides of the heel seat, the pressures will be equalized automatically in the operation of the machine.

For best results in the heel seat lasting operation it is desirable that the shoe be so supported as to permit its heel end to be centralized relatively to the wipers by the heel band while the band applies substantially equal pressures to the upper at the opposite sides of the shoe. Because of variations in the shapes and lateral locations of the cones of different lasts the spindle holes, which are usually bored each in the center of the cone of the last, are frequently not located at uniform distances from the opposite side faces of the heel-end portions of the lasts. The machine herein shown is accordingly further provided with shoe-supporting means constructed to permit bodily movement of the shoe laterally so that the heel-end portion of the shoe may be centralized by the heel band, the construction shown being such that the position of the heel seat relatively to the plane of the wipers is substantially unaffected by the bodily movement. For the purpose in view there is pivotally

connected to the casing 100 for swinging movements about an axis extending lengthwise of the shoe a member 110 in which the post 102 is slidably mounted for movements in directions heightwise of the shoe. As shown, particularly in Fig. 2, the casing 100 is provided with trunnions 112 and 114 arranged to extend loosely into aligned bores formed in the lower portion of the member 110 in locations comparatively remote from the shoe, the construction being such that the member 110 and the post 102 may swing about the axis of the trunnions in either direction to permit bodily movement of the shoe laterally to position its heel-end portion laterally in proper relation to the wipers. If the heel-end portion of the last is non-symmetrical, the spindle hole in the last will be located nearer one side of the shoe than the other side, as illustrated in Fig. 3, so that swinging movements of the member 110 in opposite directions are required to centralize right and left shoes respectively in relation to the wipers. Since the axis of the trunnions 112, 114 is so far below the shoe, such bodily lateral movement of each shoe as is required for the purpose in view is without any substantial effect on the relation of the heel seat to the plane of the wipers determined by the position of the block 108 in its guideway 106. The member 110 and post 102 are normally held centralized by a spring 116 which is mounted in a recess in a block 118 secured to the member 110. The spring is held under compression between disks 120 which are slidably movable in the recess in which the spring is mounted and are arranged to engage the inner side faces of a pair of spaced projections 122 on the casing 100. It will be evident that, while the member 110 and post 102 are normally centralized by the spring 116, they may be swung in either direction by the operator about the axis of the trunnions 112, 114 against the resistance of the spring to position the heel-end portion of the shoe properly within the heel band as the shoe is presented to the machine or such movement may be effected by the heel band as it is closed about the heel end of the shoe in the power operation of the machine.

In right or left lasts of the same style the spindle holes are usually located in substantially the same positions relatively to the opposite side faces of the heel-end portions of the lasts and accordingly, in order to assist the operator in presenting the shoes to the machine, it is desirable that means be provided for limiting the swinging movement of the member 110 and the post 102 laterally of the machine. For this purpose there is slidably mounted in a guideway on the casing 100 for movements in directions heightwise of the shoe a plate 124 which is provided with a central slot 126 (Fig. 3). At its upper end the plate 124 has a pair of inclined surfaces 128 which extend upwardly and outwardly from the opposite side faces of the slot 126, and projecting from the member 110, substantially midway between the axis of the trunnions 112, 114 and the upper end of the member, is a pin 130 which is arranged to engage one or the other of the inclined surfaces 128 to limit swinging movement of the member 110 and the post 102 in either direction. The plate 124 is movable along its guideway by means of a stud 132 which is threaded into the plate and extends outwardly into a convenient position to be grasped by the hand of the operator. It will be evident that the limits of swinging movement

of the member 110 and the post 102 may be varied and determined by movement of the plate 124 to adjust the positions of the inclined surfaces 128 relatively to the pin 130. For holding the plate

- 5 124 in adjusted position there is provided a spring-pressed detent 134 carried by the casing 100 and arranged to engage any one of a series of teeth 136 formed upon the right-hand edge face of the plate (Fig. 3). It will be understood that the angle formed by each inclined surface 128 and the side face of the slot 126 is the same so that the operator, in presenting to the machine shoes of the same style may swing the jack in either direction to locate the heel ends 15 of right or left shoes in the proper relation to the heel band and to the wipers. To lock the heel post 102 and the member 110 against swinging movement laterally of the shoe, which sometimes may be desirable, particularly when operating on shoes mounted on lasts the heel-end portions of which are symmetrical, the plate 124 may be moved upwardly until the pin 130 enters the slot 126.

Having described the invention, what I claim 25 as new and desire to secure by Letters Patent of the United States is:

1. In a lasting machine, the combination with shoe-supporting means, of end-embracing wipers, means for imparting to said wipers bodily advancing movement lengthwise of the shoe, and guiding means for the wipers operative in response to the movement of the wipers lengthwise of the shoe to impart to them closing movements laterally of the shoe, said guiding means being adjustable 35 to vary the amount of the closing movements of the wipers.

2. In a lasting machine, the combination with shoe-positioning means, of end-embracing wipers, means for imparting to said wipers bodily advancing movement lengthwise of the shoe, and devices operated by said last-named means for imparting to said wipers closing movements laterally of the shoe, said devices being constructed to impart to the wipers an adjustably variable 45 amount of additional closing movement in response to the movement of the wipers lengthwise of the shoe.

3. In a lasting machine, the combination with shoe-positioning means, of end-embracing wipers, means for imparting to said wipers bodily advancing movement lengthwise of the shoe, and means for guiding the wipers in their movement lengthwise of the shoe and for imparting to them in response to such movement closing movements 55 laterally of the shoe, said guiding means comprising members located at opposite sides of the shoe and having roll and slot connections with said wipers, the members being adjustable to vary the angular relation of the slots to the direction of lengthwise movement of the wipers to cause the wipers to swing laterally of the shoe amounts determined by the positions of said slots.

4. In a lasting machine, the combination with shoe-positioning means, of end-embracing wipers, means for imparting to said wipers bodily advancing movement lengthwise of the shoe, slides movable laterally of the shoe for closing the wipers inwardly over the shoe, plates having roll and slot connections with said wipers for connecting said closing slides to said wipers, the slots in said plates extending in directions lengthwise of the shoe, and means for adjusting the plates relatively to the slides to position said slots in variable angular relation to the direction of movement of said wipers lengthwise of the shoe

and thus to cause variable amounts of additional closing movements to be imparted to the wipers in response to their movement lengthwise of the shoe.

5. In a lasting machine, the combination with shoe-positioning means, of end-embracing wipers, means for imparting to said wipers bodily advancing movement lengthwise of the shoe, and devices movable inwardly at opposite sides of the shoe for imparting to said wipers closing movements laterally of the shoe, said devices including guiding means for the wipers operative in response to movement of the wipers lengthwise of the shoe to impart to them additional closing movements.

6. In a lasting machine, the combination with shoe-positioning means, of end-embracing wipers mounted for bodily advancing movement lengthwise of the shoe and for closing movements laterally of the shoe, means for imparting to said wipers their advancing movement, and means for closing the wipers in response to their advancing movement, said means being constructed to impart to one of said wipers a greater closing movement than that imparted to the other of said wipers.

7. In a lasting machine, the combination with shoe-positioning means, of end-embracing wipers, means for imparting to said wipers bodily advancing movement lengthwise of the shoe, and means controlled by said last-named means for imparting to the wipers in their advancing movement closing movements laterally of the shoe, said closing means being constructed to permit the amount of closing movement imparted to one 35 of the wipers to be varied independently of the amount of closing movement imparted to the other of said wipers.

8. In a lasting machine, the combination with shoe-positioning means, of end-embracing wipers, means for imparting to said wipers bodily advancing movement lengthwise of the shoe, means for guiding the wipers in their movement lengthwise of the shoe and for imparting to them in response to such movement closing movements 40 laterally of the shoe, said guiding means comprising members located at opposite sides of the shoe and having roll and slot connections with said wipers, and means for adjusting the guiding members separately to vary the angular relation 45 of each slot to the direction of lengthwise movement of the wipers to vary the amount of closing movement imparted to each wiper independently of the amount of closing movement imparted to the other wiper.

9. In a lasting machine, the combination with shoe-positioning means, of end-embracing wipers mounted for bodily advancing movement lengthwise of the shoe and for swinging or closing movements laterally of the shoe each about an axis 60 located at an end of the shoe, an operating member mounted for rectilinear movement lengthwise of the shoe to advance the wipers over the shoe, slides movable laterally of the shoe for closing the wipers inwardly over the shoe, a member carried by each of said slides and having a roll and slot connection with one of the wipers for guiding the wipers in their lengthwise movement, each of the slots being disposed at an angle 65 to the direction of lengthwise movement of the wipers to cause the wipers to swing farther inwardly over the shoe in response to their lengthwise movement, and separate means for adjusting each of the members relatively to its slide 70

to vary the angular position of its slot and thus to vary the amount of inward movement imparted to each wiper.

10. In a lasting machine, the combination with shoe-positioning means, of end-embracing wipers mounted for bodily advancing movement lengthwise of the shoe and for closing movements laterally of the shoe, means for imparting to said wipers advancing movement, devices movable inwardly at opposite sides of the shoe for imparting to said wipers their closing movements, means arranged to act through said devices to impart to the wipers swinging movements toward or from each other to vary the initial positions of the wipers widthwise of the shoe to accommodate shoes of different sizes, a member carried by each of said devices and having a roll and slot connection with one of the wipers, each of the slots extending lengthwise of the shoe at an angle to the direction of the lengthwise movement of the wipers to cause additional swinging movements to be imparted to the wipers in response to their lengthwise movement, and means to adjust each member separately about an axis so located as to vary the angular relation of its slot to the direction of the advancing movement of the wipers and thus to vary the amount of closing movement imparted to each wiper without altering substantially the initial positions of the wipers laterally of the shoe.
11. In a lasting machine, the combination with shoe-positioning means, of end-embracing wipers mounted for advancing movement lengthwise of the shoe and for swinging or closing movements laterally of the shoe each about an axis located at an end of the shoe, an operating member mounted for rectilinear movement lengthwise of the shoe for advancing the wipers over the shoe, slides at opposite sides of the shoe movable laterally of the shoe for closing the wipers inwardly over the shoe, a plate carried by each of said slides having a roll and slot connection with one of the wipers for guiding the wipers during their movement lengthwise of the shoe, each of the slots extending lengthwise of the shoe at an angle to the direction of movement of said operating member to cause the wipers to receive additional closing movements in response to their movement lengthwise of the shoe, and means for adjusting each plate relatively to its slide about an axis so located as to vary the angular relation of its slot to the direction of advancing movement of the wipers and thus to vary the amount of closing movement imparted to each wiper without altering substantially the positions of the wipers relatively to each other laterally of the shoe at the beginning of their closing movements.

12. A heel seat lasting machine having, in combination, a heel band for clamping a shoe upper about the heel end of a last, wipers for wiping the margin of the upper into lasted position at the opposite sides of the heel seat simultaneously, and a shoe support comprising a plurality of members mounted for tipping movements about different axes extending lengthwise of the shoe, said axes being so located as to permit bodily movement of the shoe laterally to centralize the heel end of the shoe in said heel band while permitting the shoe also to be tipped relatively to the wipers to position the heel seat in proper relation to the plane of the wipers without any substantial lateral displacement of the shoe.

13. A heel seat lasting machine having, in combination, a heel band for clamping a shoe upper

about the heel end of a last, wipers for wiping the margin of the upper into lasted position at the opposite sides of the heel seat simultaneously, and a shoe support comprising different members mounted for tipping movements about different axes extending lengthwise of the shoe, one of said members being mounted for tipping movements about an axis located a substantial distance below the last to permit bodily lateral movement of the shoe to centralize its heel end in said heel band, and said other member being mounted for tipping movements about an axis located above the last to permit the shoe to be tipped relatively to the wipers to provide for substantial equalization of the pressure of the wipers on the shoe bottom at the opposite sides of the heel seat without any substantial bodily lateral displacement of the shoe.

14. A heel seat lasting machine having, in combination, a heel band for clamping a shoe upper about the heel end of a last, wipers for wiping the margin of the upper into lasted position at the opposite sides of the heel seat simultaneously, and a shoe support comprising a member mounted for swinging movements about an axis located below the shoe to permit the heel end of the shoe to be centralized in the machine in response to pressure of the heel band on the shoe, and a member mounted on said last-named member for tipping movements about an axis located substantially in the plane of the heel seat of the shoe to permit the shoe to be tipped relatively to the wipers to position the heel seat in proper relation to the plane of the wipers without any substantial bodily displacement of the shoe laterally.

15. A heel seat lasting machine having, in combination, a heel band for clamping a shoe upper about the heel end of a last, wipers for wiping the margin of the upper into lasted position at opposite sides of the heel seat simultaneously, a spindle for engaging the heel end of the last in its spindle hole, said spindle being mounted for movement about an axis extending lengthwise of the shoe substantially in the location of the heel seat to permit the shoe and last to be tipped relatively to the wipers to position the heel seat in proper relation to the plane of the wipers, and a member on which said spindle is supported and relatively to which it is thus movable, said member being mounted for movement about an axis extending lengthwise of the shoe in a location a considerable distance below the shoe to permit bodily lateral movement of the spindle and the shoe to centralize the heel end of the shoe in said heel band without any substantially heightwise displacement of the opposite sides of the heel seat relatively to the wipers.

16. A heel seat lasting machine having, in combination, a heel band for clamping a shoe upper around the heel end of a last, wipers for wiping the margin of the upper into lasted position at the opposite sides of the heel seat, a spindle for engaging the heel end of the last in its spindle hole, a member on which said spindle is supported, a post having an arc-shaped guideway along which said member is movable about an axis extending lengthwise of the shoe substantially in the location of the heel seat by action of the last on the spindle to permit the shoe and last to be tipped relatively to the wipers for substantially equalizing the pressures of the wipers on the opposite sides of the heel seat, said post being mounted for movement

about an axis substantially parallel to the axis of tipping movement of the spindle to permit the position of the spindle laterally of the machine to be varied to centralize the heel-end portion of the shoe in said heel band.

17. A heel seat lasting machine having, in combination, a heel band for clamping a shoe upper about the heel end of a last, a spindle for engaging the heel end of the last in its spindle hole, a post for supporting said spindle, said post being mounted for swinging movements about an axis extending in directions lengthwise of the shoe and in a location below the shoe to permit bodily movement of the shoe laterally to centralize the heel end of the shoe in said heel band, and means for locking said post in a centralized position with respect to such swinging movement, said locking means being adjustable to release the post for limiting swinging movement laterally of the machine in either direction.

18. A heel seat lasting machine having, in combination, a heel band for clamping a shoe upper around the heel end of a last, a spindle for engaging the heel end of the last in its spindle hole, a post for supporting said spindle, a member in which said post is slidably mounted for movements in directions heightwise of the shoe, said last-named member being mounted for swinging movements about an axis extending lengthwise of the shoe and in a location below the shoe to permit the post to be swung laterally to centralize the heel end of the shoe in said heel band, a support for said last-named member, spring means for normally centralizing said swinging member with respect to its support, and means for limiting the movement of said swinging member in either direction relatively to its support, said means being adjustable to lock said member against swinging movement in the position determined by said spring means.

19. A heel seat lasting machine having, in combination, a heel band for clamping a shoe upper around the heel end of a last, wipers for wiping the margin of the upper into lasted position at the opposite sides of the heel seat simultaneously, a spindle for engaging the heel end of the last in its spindle hole, said spindle being mounted for movement about an axis extending in di-

rections lengthwise of the shoe substantially in the location of the heel seat to permit the shoe and last to be tipped relatively to the wipers to position the heel seat in proper relation to the plane of the wipers, a post supporting said spindle and relatively to which the spindle is thus movable, said post being mounted for swinging movement about an axis extending lengthwise of the shoe in a location a considerable distance below the shoe to permit the position of the spindle laterally of the machine to be varied to centralize the heel-end portion of the shoe in said heel band, spring means for normally centralizing said post with respect to such swinging movement, and means for locking said post in a centralized position, said locking means being adjustable to permit limited swinging movement of the post laterally of the machine in either direction.

20. A heel seat lasting machine having, in combination, a heel band arranged for clamping a shoe upper around the heel end of a last, wipers for wiping the margin of the upper into lasted position at the opposite sides of the heel seat, a spindle for engaging the heel end of the last in its spindle hole, said spindle being mounted for movements about an axis extending lengthwise of the shoe substantially in the location of the heel seat to permit the shoe and last to be tipped relatively to the wipers to position the heel seat in proper relation to the plane of the wipers, spring means for normally centralizing said spindle with respect to such tipping movements while permitting it to be tipped by action of the last thereon, a post for supporting said spindle and relatively to which the spindle is thus movable, said post being mounted for swinging movements about an axis substantially parallel to the axis of tipping movement of said spindle and in a location below the shoe to permit the position of the spindle laterally of the machine to be varied to centralize the heel end of the shoe in said heel band, and spring means for normally centralizing said post with respect to such swinging movement while permitting it to be swung by the operator in presenting the shoe to the machine.
